ABSTRACT OF THE DISCLOSURE

A dial pin for a watch having a cylindric portion dimensioned for snug receipt within an aperture in the watch plate and a head portion having a frusto-conical collar portion extending radially from and eccentrically disposed relative to said cylindric portion with the base of larger diameter of said frusto conical collar portion being adjacent to said cylindric portion.

This invention relates to a dial pin for fixing a watch dial to the plate easily and surely.

The fixing of the dial is ordinarily ensured by the construction wherein the point of the dial screw or the conical part of flush screw head in the tapped hole drilled in the side of the plate locks the dial foot.

However, this construction heretofore used, has the disadvantage that after a long use or a slight shock the dial screw becomes loose, the dial loosens, and the dial screw drops into the movement and stops it.

This invention is directed to the remedy of these disadvantages.

An object of this invention is the provision of a dial pin which can fix the dial easier and surer by using an eccentric pin instead of screw.

The invention will be better understood from the following description taken in connection with the accompanying drawings in which:

FIG. 1 is a plan view of embodiment of this invention.

FIG. 2 is a sectional view, taken along the line A—A' of FIG. 1.

Referring now to the drawings, 1 denotes the dial pin, comprising a thin cylindric portion 1a, a truncated conical collar portion 1b to engage at the dial foot 4 and a head portion 1c provided with a slot. The dial 3 is provided with dial foot 4. In said dial pin 1, the thin cylindric portion 1a and the collar portion 1b are eccentric and the center of rotation of the dial pin 1 is that of the thin cylindric portion 1. The thin cylindric portion 1a of said dial pin 1 tightly fits within an aperture in the plate 2, said tight fit permitting the rotation of said dial pin 1. The fitting of the cylindric portion 1a within the aperture in the plate scarcely changes after rotation of said dial pin, due to the elastic effect of the cylindric portion 1a which forms a thin cylinder having center hole 1d.

2

OPERATION OF DIAL PIN

When setting of dial 3 on the plate 2, the collar portion 1b of the dial pin 1 is maintained away from the dial foot 4 as shown in FIG. 1 by a two-dot chain line. After setting the dial on the plate 2, the dial pin 1 is turned and the collar portion 1b is driven into the dial foot 4, as shown in full line in FIG. 1 and in FIG. 2. As the dial pin 1 is provided with a slot in the head portion 1c, said dial pin can be easily turned by a screwdriver. When so positioned, the force of the dial pin 1, in resisting the loosening of the dial 3 from plate 2, acts the direction whereof the dial pin is maintained against the plate. In addition, the dial pin 1 has an elasticity which tends to resist the turning of said dial pin 1 due to the loosening thereof.

According to the present invention, the fitting of the said dial on the plate is easily achieved. Further, the loosening of the dial, the loosening of the dial pin and falling out of the said pin will not occur. Moreover, as there is no necessity for thread cutting, said pin can be manufactured at low cost.

I claim:

1. A dial pin for a watch having a plate formed with a pair of spaced first and second apertures therein and a dial having a foot extending through a first of said apertures, said dial pin comprising a cylindric portion formed with a bore therethrough defining a tubular cross section dimensioned for snug receipt within said second plate aperture; and a head portion having a collar portion projecting radially outwardly from said cylindric portion and eccentrically disposed relative to said cylindric portion, said collar portion being tapered inwardly from the side thereof adjacent said cylindric portion, said collar portion being dimensioned so that one peripheral region thereof is engageable against said dial foot when said cylindric portion and said dial foot are positioned respectively in said first and second plate apertures and another peripheral portion thereof is not so engageable when said cylindric portion and dial foot are so positioned.

2. A dial pin as recited in claim 1, wherein said collar portion is frusto-conical, with the base thereof of greater diameter being adjacent said cylindric portion.
